UNITED STATES PATENT OFFICE

THOMAS C. MUSSEN, OF TORONTO, ONTARIO, CANADA

DESIGN FOR A VEHICLE WHEEL

Application filed January 24, 1931. Serial No. 38,439. Term of patent 7 years.

To all whom it may concern:

Be it known that I, THOMAS C. MUSSEN, a subject of the King of Great Britain, residing at the city of Toronto, in the county of York, Province of Ontario, Canada, have invented a new, original, and ornamental Design for Vehicle Wheels, of which the following is a specification, reference being had to the accompanying drawings, forming part thereof, in which—

Fig. 1 is a side elevation of the wheel; and
Fig. 2 a vertical section.

The dominant features of the design lie in the ring like spokes being circular in cross section with their outer edges abutting and arranged in a concave or dished relation to the wheel.

I claim:

The ornamental design for a vehicle wheel, as shown and described.

THOMAS CHARLES MUSSEN,
